(57) **CLAIM**

The ornamental design for a latch for a handbag, as shown and described.

DESCRIPTION

FIG. 1 is a perspective view of a latch for a handbag, showing the latch closed.

FIG. 2 is a perspective view of the latch of FIG. 1, showing the latch closed.

FIG. 3 is a top plan view of the latch of FIG. 1, showing the latch closed.

FIG. 4 is a bottom plan view of the latch of FIG. 1, showing the latch closed.

FIG. 5 is a back elevational view of the latch of FIG. 1, showing the latch closed.

FIG. 6 is a front elevational view of the latch of FIG. 1, showing the latch closed.

FIG. 7 is a left side elevational view of the latch of FIG. 1, showing the latch closed.

FIG. 8 is a right side elevational view of the latch of FIG. 1, showing the latch closed.

FIG. 9 is a perspective view of a first latch component of the latch of FIG. 1, showing the first latch component in an open position.

FIG. 10 is another perspective view of the first latch component of FIG. 9, showing the first latch component in an open position.

FIG. 11 is a top plan view of the first latch component of FIG. 9, showing the first latch component in an open position.

FIG. 12 is a bottom plan view of the first latch component of FIG. 9, showing the first latch component in an open position.

FIG. 13 is a left side elevational view of the first latch component of FIG. 9, showing the first latch component in an open position.

(Continued)

FIG. 14 is a right side elevational view of the first latch component of FIG. 9, showing the first latch component in an open position.

FIG. 15 is a back elevational view of the first latch component of FIG. 9, showing the first latch component in an open position.

FIG. 16 is a front elevational view of the first latch component of FIG. 9, showing the first latch component in an open position.

FIG. 17 is a perspective view of a second latch component of the latch of FIG. 1.

FIG. 18 is another perspective view of the second latch component of FIG. 17.

FIG. 19 is a top plan view of the second latch component of FIG. 17.

FIG. 20 is a bottom plan view of the second latch component of FIG. 17.

FIG. 21 is a left side elevational view of the second latch component of FIG. 17.

FIG. 22 is a right side elevational view of the second latch component of FIG. 17.

FIG. 23 is a back elevational view of the second latch component of FIG. 17; and,

FIG. 24 is a front elevational view of the second latch component of FIG. 17.

The dash-dot-dot broken lines immediately adjacent the shaded areas represent the bounds of the claimed design while the dash-dash broken lines show portions of the latch for a handbag that form no part of the claimed design. The broken lines form no part of the claimed design.
